UNITED STATES PATENT OFFICE

2,650,712

ENGINE FILTER

John C. Slonneger, Dallas, Tex., assignor to The Continental Supply Company, Dallas, Tex., a corporation of Delaware

Application May 1, 1948, Serial No. 24,607, which is a division of application Serial No. 654,427, March 14, 1946. Divided and this application November 10, 1949, Serial No. 126,540

1 Claim. (Cl. 210—170)

1

This invention relates to new and useful improvements in engine oil pumps and filters.

One object of the invention is to provide a pump and filter or screen arrangement, whereby the screen is readily accessible from the outside of the crankcase and easily removed from the pump and the crankcase through an opening in one of the case walls.

Another object of the invention is to provide a screen arrangement whereby the screen is attached to a cover plate and is detachably connected to the pump, so that when said plate is removed it detaches the screen from the pump and removal of the plate also removes the screen from the crankcase.

Still another object of the invention is to provide a detachable, yet liquid tight connection, between the screen and the pump.

A construction designed to carry out the invention will be hereinafter described together with other features of the invention.

The invention will be more readily understood from a reading of the following specification and by reference to the accompanying drawings, wherein an example of the invention is shown, and wherein:

Fig. 1 is a partial, longitudinal sectional view of an engine equipped with a pump and screen constructed in accordance with the invention,

Fig. 2 is a perspective view, partly in elevation and partly in section, showing a lubricating unit constructed in accordance with the invention, and

Fig. 3 is a longitudinal sectional view of the screen and component parts.

This application is filed as a division of my co-pending application filed May 1, 1948, Serial No. 24,607, which in turn was a division of my then co-pending application, filed March 14, 1946, Serial No. 654,427, now Patent Number 2,590,134.

In the drawings the numeral 19 designates, in general, the crankcase of an internal combustion engine. The crankcase has a front wall 11. A lubricating unit, indicated generally by the numeral 12, includes a block 13 which is fastened or made stationary in the crankcase. A camshaft 14 is journaled vertically in said block and drives a rotary pump 15, disposed horizontally and attached to the bottom of said block. The pump has an outlet boss 16 and an oil discharge pipe 17 leads from the boss to the bottom of a vertical oil passage 18 in the block.

The pump has an inlet nipple 19 on its side facing the crankcase wall 11 and having an annular fillet 20 at its intersection with the pump. A cylindrical filter or screen 21 includes a per-

forated or foraminous shell 22, an inner end wall 23 and an outer end 24. The inner end wall has a central opening 25, the outer annular edge 26 of which is beveled, so that when the nipple 19 is received in the opening, the beveled edge will make a metal-to-metal contact with the fillet 20, whereby a liquid tight seal is had.

The front wall 11 has a circular opening 27 which is surrounded by a gasket 28 interposed between the outer face of the wall 11 and the inner face of a rectangular cover plate 29, removably fastened on said wall by stud bolts 30. The cover plate has a boss 31 at the center of its inner face and a stud bolt 32 has its outer end screwed into this boss. The bolt extends through an aperture 33 in the outer end wall 24 of the screen and has a nut 32' adapted to engage the inner side of said wall. The aperture 33 is continued through a boss 35 on the outer side of the wall 24. The boss 35 is directed toward the boss 31 and is preferably of the same diameter so as to support a coil spring 36, having its ends bearing against the plate 29 and the end wall 24 of the screen. The spring being under compression holds the screen 21 on the nipple 19 and against the fillet 20 so as to form a liquid-tight joint.

Since the screen is immersed in the body of oil in the crankcase 10, it may be filled with filtering material if desired; however the perforations in the wall 22 may be of such size as to filter the oil passing therethrough. By reason of the spring 36, the screen is yieldably mounted on the pump and slidably mounted on the bolt 32. The bolt 32 being secured to cover plate 29 and the screen being supported by said bolt, it is obvious that when said plate is removed and pulled outwardly, the screen will be withdrawn from the pump 15 through the opening 27. The screen is readily replaced. When the screen is replaced on the nipple 19 and the cover plate is fastened in place, there may be some slack, but the spring 36 will force the beveled edge 26 of end wall 24 against the fillet 20 and may itself be further compressed when the bolts 30 are tightened.

The foregoing description of the invention is explanatory thereof and various changes in the size, shape and materials, as well as in the details of the illustrated construction may be made, within the scope of the appended claim, without departing from the spirit of the invention.

What I claim and desire to secure by Letters Patent is:

A lubricating oil screen for use in an engine crankcase on the intake of an engine oil pump having a short intake nipple directed toward one

wall of the crankcase, said oil screen including an imperforate cover plate adapted to be secured to the crankcase wall, a bolt immovably secured to and rigidly extending from the plate, an elongate unitary foraminous screen having one end slidably mounted on the bolt, retaining means on the bolt within the screen limiting longitudinal movement of the screen on the bolt away from the plate, a coiled spring between the screen and the plate constantly urging the screen from the plate, the screen having at its opposite end a support adapted to engage the intake nipple, and axially aligned bosses on the cover plate and the screen surrounding the bolt, the spring encompassing said bosses.
